UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

DROP DOOR FOR RAILWAY CARS

Application filed April 25, 1929. Serial No. 358,009.

The invention relates to railway cars of the dumping type but more specifically to the so-called "general service" gondola cars wherein the floor consists of a plurality of doors, which doors usually have one end hinged to the center construction of the car and the other end supported by the side wall of the car when the door is in closed position. Such doors are usually each provided with a plurality of hinge elements and support elements, and I provide a beam element between each hinge element and its opposite supporting element. When two hinges are used to each door each of such beams supports substantially 50% of the load imposed upon the door and where three hinge elements are used each beam supports substantially one-third of the load imposed upon the door.

Such cars are provided with stops adjacent the sides of the door opening to restrict the downward movement of the door and the door is provided with bumpers to engage these stops. The stops are usually spaced to divide the length of the door into thirds according to known mechanical principles. I provide a beam element extending between the bumpers on the door which is substantially normal to the beam element extending between the hinge and supporting elements. When the door is dropped the load follows the door and at the moment of impact of the bumpers with the stops, this beam element carries substantially two-thirds of the load imposed upon the door. (See Fig. 2.)

The object of this invention is to provide a hinged door for a railway car, which door is reinforced by beam elements which function when the door is in closed position and another beam element which functions when the door is in open position. Another object of the invention is to secure co-operation between these different beam elements whereby each beam element reinforces each other beam element.

In the drawings:

Figs. 1, 2 and 3 show a typical application of my invention to a railway car.

Figs. 4, 5 and 6 show the typical door in detail.

In the drawings, the usual parts of the car are shown, such as center sills or center construction 1; cover plate 2; cross diaphragms 3; side wall 4; operating shaft 5; raising chain 6 and stop 7. The door is provided with hinge elements 8 adjacent one end thereof, which engage hinges 9 mounted on the center construction. The door is also provided with support elements 10 adjacent the other end of the door to which the raising chain 6 is secured. The term "support elements" means any means adjacent the outer end of the door which supports the door upon a part of the car proper when it is in closed position. The door is provided also with bumpers 12 preferably positioned adjacent the opposite sides of the door which engage the stops 7 on the car body when the door is in open or lowered position.

The door is provided with a rib or other reinforcement 15 on each side of the door, each of which ribs extend from a hinge element 8 to the bumper 12 and therebeyond to the support element 10. Effectively the beam element extends from the hinge element 8 to the support element 10 and is deflected so as to pass through the bumper. The door is also provided with a preferably deeper rib or reinforcement 16 extending between the bumpers on the opposite sides of the car and preferably merging at its opposite ends into the first mentioned ribs 15. The different beam elements merge into each other and are so formed as to prevent either one of them from deflecting under stress, thereby co-operating to strengthen each of them. I also preferably provide the buttresses or brackets 17 which prevent the beam element from deflecting.

I preferably provide a rib or flange 20-21 between the hinge elements and support elements, respectively, to hold them in proper position and also prevent the door body from deflecting between these elements. Brackets 22-23 are also provided extending from the beam elements toward the corners 100

of the door to prevent the corners from drooping.

As the rib element 16 forming the beam elements between the bumpers 12 may support a greater load than the other beam elements (15) they are preferably deeper so as to make them relatively stronger.

In my co-pending application Serial No. 358,008, filed April 25, 1929, I have described and claimed a door having a beam element extending between hinge and support elements and another beam element extending between bumpers on the door.

The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. A door for a railway dump car comprising hinge elements adjacent one end thereof, support elements adjacent the other end thereof, bumpers adjacent the opposite sides thereof, and a rib on each side of the door, each of said ribs extending from a hinge element to a support element and deflected so as to pass through a bumper.

2. A door for a railway dump car comprising hinge elements adjacent one end thereof, support elements adjacent the other end thereof, bumpers adjacent the opposite sides thereof, a rib on each side of the door, each of said ribs extending from a hinge element to a support element and deflected so as to pass through a bumper, and another rib extending between said bumpers.

3. A door for a railway dump car comprising hinge elements adjacent one end thereof, support elements adjacent the other end thereof, bumpers adjacent the opposite sides thereof, a rib on each side of the door, each of said ribs extending from a hinge element to a support element and deflected so as to pass through a bumper, and a deeper rib extending between said bumpers.

4. A door for a railway dump car comprising hinge elements adjacent one end thereof, support elements adjacent the other end thereof, bumpers adjacent the opposite sides thereof, a rib on each side of the door, each of said ribs extending from a hinge element to a support element and deflected so as to pass through a bumper, and another rib extending between said bumpers and merging into said first mentioned ribs.

5. A door for a railway dump car comprising hinge elements adjacent one end thereof, support elements adjacent the other end thereof, bumpers adjacent the opposite sides thereof, a rib on each side of the door, each of said ribs extending from a hinge element to a support element and deflected so

as to pass through a bumper, another rib extending between said bumpers, and brackets extending from the first mentioned ribs toward the corners of the door.

6. A door for a railway dump car comprising hinge elements adjacent one end thereof, support elements adjacent the other end thereof, bumpers adjacent the opposite sides thereof, a rib on each side of the door, each of said ribs extending from a hinge element to a support element and deflected so as to pass through a bumper, another rib extending between said bumpers, and a flange connecting adjacent hinge elements. 70

7. A door for a railway dump car comprising hinge elements adjacent one end thereof, support elements adjacent the other end thereof, bumpers adjacent the opposite sides thereof, a rib on each side of the door, each of said ribs extending from a hinge element to a support element and deflected so as to pass through a bumper, another rib extending between said bumpers, a flange connecting adjacent hinge elements, and another flange connecting adjacent support elements. 80

8. A door for a railway dump car comprising hinge elements adjacent one end thereof, support elements adjacent the other end thereof, bumpers adjacent the opposite sides thereof, a rib on each side of the door, each of said ribs extending from a hinge element to a support element and deflected so as to pass through a bumper, a deeper rib extending between said bumpers and merging into said first mentioned ribs, brackets extending from the first mentioned ribs toward the corners of the door, a flange connecting adjacent hinge elements, and another flange connecting adjacent support elements. 95

9. In a railway car having a door opening and a door therefor, the combination of hinge members adjacent one end of the opening, support members adjacent the opposite end of the opening to support the door in closed position, and door stops on the opposite sides of the opening to support the door in open position, said door provided with a rib extending between each hinge member and the opposite support member deflected so as to pass adjacent said stops, and another rib extending between the portions of the door which engage said stops. 110

ARTHUR E. SMALL. 115
